FIG. 1

FIG. 2

FIG. 4

FIG. 3

FIGURE 1 is a perspective view of a railway car showing our new design;

FIGURE 2 is a side elevational view of the railway car shown in FIGURE 1;

FIGURE 3 is an end elevation of the railway car shown in FIGURE 1; and

FIGURE 4 is a cross section of the railway car of FIGURE 1 illustrating the shape of the railway car body.

The side and end of the railway car not shown in the drawings are substantially the same as those shown.

The present application is a continuation-in-part of design application Serial No. D. 77,913, filed December 23, 1963, and now abandoned.

The dominant features of our design reside in the shape of the railway car body shown in full lines.

We claim:

The ornamental design for a railway car, as shown and described.
